By Frank W. Hoens,
ATTORNEY.

UNITED STATES PATENT OFFICE.

LLOYD KELCH, OF WABASH, INDIANA, ASSIGNOR OF ONE-HALF TO FORD METER BOX COMPANY, OF WABASH, INDIANA.

DESIGN FOR AN ASH-TRAY.

57,913.

Specification for Design.

Patented May 17, 1921.

Application filed April 24, 1920. Serial No. 376,415. Term of patent 7 years.

To all whom it may concern:

Be it known that I, LLOYD KELCH, a citizen of the United States, residing at Wabash, in the county of Wabash and State of Indiana, have invented a new, original, and ornamental Design for an Ash-Tray, of which the following is a specification, reference being had to the accompanying drawings, forming part thereof.

Figure 1 is a top or plan view of an ash tray, showing my new design. Fig. 2 is a side view of the ash tray, showing my new design.

I claim:

The ornamental design for an ash tray, as shown.

LLOYD KELCH.
